SILVESTRO MILANO, OF NEW YORK, N. Y.

BURGLAR-ALARM.

1,163,164.

Specification of Letters Patent.

Patented Dec. 7, 1915.

Application filed December 27, 1912. Serial No. 738,839.

To all whom it may concern:

Be it known that I, SILVESTRO MILANO, a citizen of the United States, residing in the city of New York, borough of Bronx, county and State of New York, have invented a certain new and useful Burglar-Alarm, of which the following is a specification.

This invention is a burglar alarm, the same being adapted for use on a door or a window for the purpose of automatically giving an alarm when an attempt is made to open the door or window.

The invention consists of a base having means for holding a cartridge, a plunger supported on the base for slidable and rotative movement thereon, a spring for operating the plunger, means for retaining the plunger in a retracted position, and a trip member movable with the plunger. Said trip member is pivoted to the plunger, whereby said trip is adapted to be folded to assume an out of service position when the alarm is not to be used, such adjustment being effected while the plunger is in a retracted position, but when the alarm is to be set for use, then the trip member should be positioned at an angle to the plunger, whereupon the trip member is locked to the plunger by the adjustment of a locking member, preferably in the form of a slideable sleeve.

In the accompanying drawings, I have illustrated different practical embodiments of the invention, but the constructions shown therein are to be understood as illustrative, only, and not as defining the limits of the invention.

Figure 1 is a front elevation of my device applied to the casing and a door, the alarm device being illustrated for the trip member thereof to lie in the path of the door, said door and the casing being indicated in dotted lines. Fig. 2 is a front elevation of the alarm device with the trip member in a folded inoperative position. Fig. 3 is a side elevation illustrating the plunger in the position which it assumes subsequent to explosion of the cartridge, the dotted lines illustrating the adjusted position of the plunger prior to contact with the cartridge. Fig. 4 is a plan view of the invention adapted for use in connection with the meeting rails of window sashes.

The burglar alarm illustrated in Figs. 1,

2 and 3 is especially adapted for use on the casing G of a door G', the parts being illustrated in dotted lines in Fig. 1.

The working parts of the device are mounted on a base member A, the latter being provided near its respective end portions with apertures *a'* adapted to receive screws by which the base member is fastened firmly in place on the door casing G. Near one end the base member is provided with a lug B adapted to receive a cartridge *b* to be exploded by the movement of a plunger C. The lug B may be constructed in any suitable way to receive the cartridge; ordinarily it is sufficient to provide the lug with a recess within which the cartridge *b* is adapted to be inserted by hand. It is apparent that the cartridge should be positioned in the path of movement of the plunger C in order that the impact of the plunger may explode the cartridge. Ordinarily, a blank cartridge is used. The plunger C is fitted loosely in lugs *c c'*, the latter being integral with the base member. Said plunger is slidable and rotatable in the lugs, and the movement of the plunger in one direction is due to the action on said plunger of a coiled spring D, whereby the plunger when tripped is impelled with considerable force toward and into contact with the cartridge for the purpose of exploding the latter and giving the desired alarm. In addition to the guide lugs *c*, the base member is provided with a pair of locking lugs *a* between which the end portion of the plunger is slid able, said plunger being rotatable between the lugs *a a* in order that the bent end C' of the plunger may have locking engagement with one lug or the other *a*, whereby the plunger may be retained by engagement with one of the lugs in the desired retracted position in order to set the device for use.

The plunger C is provided intermediate its ends with a threaded portion *c'*, on which is screwed a nut *d*. A washer *d'* is in contact with the nut *d* and between this washer *d'* and the fixed guide lug *c* is positioned the spring D, whereby the spring acts through the washer and the nut to exert its expansive force against the plunger C so as to impel the latter forcibly toward the cartridge, it being observed that said spring D' is seated at one end against the stationary guide lug *c'*.

As shown, the plunger C is bent at one

end to produce a short arm C', the latter extending at a right angle to the length of the plunger. This short arm is provided with a notch in which is fitted an end portion of a trip member E, said trip member being pivoted to the short arm C' by a transverse pin e. The pivoted portion of the trip member E is beveled at e', and when the trip member is moved into alignment 5 with the arm C' said beveled end e' of the trip member is in contact with an end face of the recess in the arm C', thus limiting the pivotal movement of the trip member with respect to the plunger arm C'. The trip member is locked in fixed relation to the arm of the plunger by a locking sleeve F, the latter being slidably fitted on the member E so as to be movable to a position across the jointed connection between the 10 plunger arm C' and pivoted member E. In the operative position of the trip member with respect to the plunger the sleeve F is adjusted across the pivotal connection e so as to lock the arm E in fixed relation to the plunger, but when the device is set for service and it is desired to position the trip member out of the way of the door, then the sleeve F is withdrawn from the pivotal pin e and the member E is turned to a position 15 parallel with the plunger C, as clearly shown in Fig. 2.

The spring D and lugs c c' are incased within a suitable housing A', the latter being fitted removably to the base member A. 20 For the sake of clearness the casing A' is omitted from Fig. 1, but the position of this casing A' is indicated in Figs. 2 and 3.

In addition to the alarm, my invention embodies a safety chain adapted to be used 25 in connection with the door and the base member so as to prevent the door from being forced open by an intruder after the alarm is given. The safety chain is combined with the base member A in such a manner that the attachment of the safety chain to the base member does not in any way interfere with the operation of the alarm mechanism. Accordingly, the base member is provided at one end and at a point remote to the plunger with a fixed 30 staple or lug H, to which staple is loosely connected an end link of the safety chain H'. At the free end of this safety chain there is provided a fastening member in the 35 form of a plate h having a headed stud h', the stud projecting laterally from the plate h and formed with a recess h² between the head and the plate. The safety chain is used in connection with a keeper I, consisting 40 of a base plate provided with apertures i for the passage of screws, whereby the keeper is fastened rigidly to the door G'. This keeper is provided with a slot, one end of which is enlarged at I'. The fastening member h is adapted for engagement with

the keeper when it is desired to set the alarm and secure the door, the head h' of the fastening member being insertible into the enlarged end of the slot and slideable into the smaller part of the slot so as to detachably 70 fasten the free end of the safety chain to the keeper on the door.

The operation is as follows: The base member is fastened by screws to the door casing and the keeper I is secured in like 75 manner to the door. When it is desired to set the alarm for use the operator withdraws plunger C so as to compress the spring D and turns the plunger for the arm C' to engage one of the lugs a, thus 80 locking the plunger in a retracted position and under the tension of the spring. The operator should now insert a cartridge b into the lug B and thereafter the trip member E is turned on the pivot e so as to extend 85 across the door G', after which the sleeve F is moved along trip member E to inclose the pivotal connection e and lock the member E to the plunger C. The safety chain is now lifted and manipulated for its 90 fastener h to engage with the slotted keeper I. When pressure is applied to the door G' the arm E is pressed inward and plunger C is rotated, thus withdrawing the bent arm C' from one of the lugs, whereupon the 95 spring D impels the plunger toward the cartridge for exploding the latter, thereby giving the audible alarm. The door, however, cannot be opened, for the reason that the chain H' is engaged with the keeper, thus 100 preventing a burglar from entering the room. Should the alarm remain intact, it is not necessary to withdraw the cartridge from the lug B or to release the plunger from the lug a with which said plunger is 105 engaged, for the reason that sleeve F can be moved along the trip E, after which the trip can be turned into a folded position parallel to the plunger, as shown in Fig. 2. The safety chain can be readily disconnected 110 from the keeper and thus the entire device can be adjusted so as to permit the door to be opened and closed without setting off the alarm, or breaking the safety chain.

My invention as thus far described is 115 adapted to be used on a door and its jamb, but in Fig. 4 there is illustrated a construction of the alarm which may be employed to good advantage on the meeting rails of window sashes. The device consists of the base 120 member provided with the guide lugs c c' and the locking lugs a, the recessed lug B to receive the cartridge, the spring-operated plunger C, the trip member E pivoted to the bent arm of said plunger, and the locking sleeve F, all of which parts are constructed and adapted for operation substantially as hereinbefore described. The window fastener, however, does not require the safety chain or its keeper and, accordingly, 125

these parts are omitted. The spring and a part of the plunger are housed within the casing A'.

When it is desired to use the device of Fig. 4 the base member is secured by screws to one of the sash rails and to adapt the device for use the plunger is pulled in one direction and turned so that the bent arm of the plunger engages with one of the lugs *a*, after which the pivoted arm E is turned to a position at right angles to the plunger and the sleeve F is adjusted so as to lock the trip to the plunger. It is apparent that the base member, the plunger and the cartridge are supported on a rail of one sash, whereas the trip member is adjusted into the path of a rail on the companion sash. Should either of the sashes be moved the member E will turn the plunger in a direction to disengage it from the lug *a*, whereupon the spring forcibly impels the plunger against the cartridge in the lug B, thereby exploding the cartridge and giving the alarm.

Having thus fully described the invention, what I claim as new, and desire to secure by Letters Patent is:—

1. In a burglar alarm, the combination with a base, of a plunger supported for sliding and rotative movement thereon, said plunger being provided with an angular arm, a trip member pivoted to said arm of the plunger, said trip member being foldable parallel to the plunger and being mov-

able on the pivot to extend in line with the 35 arm of the plunger, and a sleeve for locking the trip member in fixed relation to the arm of said plunger when said trip member extends outwardly from the plunger.

2. In a burglar alarm, the combination 40 with a base, and a spring-operated firing plunger supported on the base for sliding and rotative movement thereon, of means for locking said firing plunger in a retracted position with the spring under tension, said 45 locking means being effective in retaining said plunger when it is rotated in one direction or the other from a central position, a trigger having pivotal connection with said firing plunger, said trigger being foldable 50 into an inoperative position substantially parallel to the plunger and being movable into an operative position substantially at right angles to said plunger, and trigger-locking means co-operating with the plunger and the trigger, said trigger-locking means being effective in restraining the trigger from pivotal movement in any direction relative to the plunger when said trigger is in the operative position substantially at 55 right angles to said plunger.

In testimony whereof I have signed my name to this specification in the presence of two subscribing witnesses.

SILVESTRO MILANO.
